MAINSPRING FOR WATCHES, CLOCKS, ETC.

Anton J. Anderson, Jersey City, N. J.

Application August 26, 1932. Serial No. 630,601

3 Claims. (Cl. 267—1)

This invention relates generally to the class of springs employed as motive power, and while not necessarily restricted thereto, refers more particularly to an improvement in mainsprings for 5 watches, clocks or the like.

The invention aims for its principal object to provide an improved spring of the character set forth, by virtue of which greater power is obtained from an improved spring of the same size 10 as the ordinary spring or equal power is obtained from an improved spring of a smaller size than the ordinary spring.

The invention further resides in an improved spring of the indicated character which is comparatively simple in its structure, costs but little 15 more than the ordinary spring and which is highly efficient in its purpose.

With the above recited and other objects in view, reference is had to the following description and accompanying drawing, in which there 20 is exhibited one example or embodiment of the invention, while the claims define the actual scope of the same.

In the drawing: 25 Figure 1 is a plan view of a watch spring constructed in accordance with the invention and illustrating the same located in the spring barrel.

Figure 2 is an enlarged cross sectional view taken approximately on the line indicated at 30 2—2 in Figure 1.

Referring to the drawing by characters of reference, A designates generally a watch or clock spring barrel, B the shaft, and C the improved spring, which is normally of cross curved, bowed 35 or concavo-convex cross sectional configuration throughout the major or entire length of the spring body instead of being normally flat, as has heretofore been customary. By providing the spring body of cross curved or bowed cross sectional configuration so that it inherently assumes said cross sectional curve, it will be found that more power will be derived from the same thickness than is possible from a flat spring, or a spring body of considerably lesser thickness will have 40 greater strength and afford greater power than a corresponding flat spring. In use in watches or clocks, this is a distinct advantage, in that there will be afforded in the spring barrel a greater space to permit of greater expansion of the spring 45 and a longer run of the watch from a single winding before the spring power is exhausted. Furthermore, by means of a concavo-convex spring which gives the same strength and power of a flat spring which is thicker, a spring of greater length 50 may be employed without requiring more space

in the spring barrel, which also contributes toward a longer running of the watch on a single winding. By constructing the spring in this manner, it will also be found that space is economized where it is desirable to produce watches of very 55 small sizes.

Preferably, the spring is arranged in the spring barrel with the concave side of the convolutions disposed outwardly and the convex side disposed inwardly, as clearly illustrated in Figure 2 of the 60 drawing, and it will be found that when the spring is wound, the inner convolutions will have a tendency to flatten out while the outer convolutions will be progressively curved to a greater 65 degree toward the outer end of the spring. As the spring unwinds, the convolutions inherently return to their normal curvature, thereby adding 70 to the power developed by the unwinding of the spring convolution.

While there has been illustrated and described 75 a preferred embodiment of the invention, it is to be understood that this is merely descriptive of one form, and that variations and modifications which fall within the range of the claims 80 may be resorted to when desired.

What is claimed is:

1. A spring motor spring comprising a resilient body of concavo-convex cross sectional configuration extending across the entire width of the 85 body.

2. A spring motor spring comprising a resilient body of concavo-convex cross sectional configuration extending across the entire width of the body having the convex side disposed inwardly.

3. A spring motor spring comprising a resilient 90 body inherently bowed transversely and capable of being flattened when wound up.

ANTON J. ANDERSON.
